CLAIM

The ornamental design for a display panel or screen with graphical user interface for physical fitness, as shown and described.

DESCRIPTION

FIG. 1 is a front view of a display panel or screen with graphical user interface for physical fitness showing our new design; and,

FIG. 2 is an enlarged view of the area 2 indicated by the single dot-dash broken lines in FIG. 1.

The evenly-spaced broken lines depict portions of the display panel or screen with graphical user interface for physical fitness that form no part of the claimed design. The single dot-dash broken lines in FIGS. 1 and 2 represent the boundary of an enlarged area of the design and form no part of the claimed design.
